UNITED STATES PATENT OFFICE

2,173,958

INSOLE-COVERING MACHINE

Frederic E. Bertrand, Lynn, Mass., assignor to
 United Shoe Machinery Corporation, Paterson,
 N. J., a corporation of New Jersey

Application June 3, 1938, Serial No. 211,509

45 Claims. (Cl. 12—20)

My invention relates to machines for folding the marginal portions of sheet-material with reference to the remainder of the sheet, it being herein disclosed in connection with the folding about the edge of an insole the margin of a covering-sheet which has previously been attached to said insole.

In Letters Patent of the United States No. 2,106,268, Bertrand, January 26, 1938, there is described and claimed a machine for applying to a ribbed insole a protective covering or sock-lining. To render this smooth and secure against displacement, the covering, which may be of thin leather, is preferably cemented to the tread-surface of the insole and is also carried over the edge across the feather and against the outside of the rib. To this additional area, the covering is not only adhesively attached and thereby rendered more secure, but when the welt is applied, the stitching, which passes through both the covering and the insole-rib, will positively hold said covering against slipping upon the tread-surface of the insole. This machine effects the folding and attaching operations speedily and smoothly, with little effort on the part of the operator, and in such a manner that the covering shall extend with substantial uniformity to the edge of the rib, regardless of variations in the width of the feather. It is an object of the present invention to increase still further the efficiency and ease of operation of the patented machine.

In the attainment of the above object, I guard against interference with a member which is movable across the feather of the insole to operate upon the margin of the adhering sheet, by the use of a retaining member, which may be in the form of a finger yieldable transversely of the insole-feather, which retaining member is arranged to receive engagement of the outer margin of the insole. This not only prevents the feather from rising from the table or support for the insole but also holds the coated margin of the sheet, at the side opposite that being operated upon, from premature engagement with the insole. To insure a suitable clearance between a folding and pressing member, which travels with a cutter from the margin of the cover-material across the insole-feather, and the parts upon which it is to act, this folding and pressing member is mounted upon a support for movement with the cutter and is also movable bodily on said support, so it may be caused to force the material against the insole-feather at the appropriate time in its operating movement. The folding and pressing member is shown as provided with an inclined surface, contacting in its advance with a member which urges it toward the work-supporting table, this occurring against the retracting force of a spring. A novel mounting is provided for a member which acts to press the covering-material

against the edge of the insole, together with adjusting means for its actuating spring. To allow the elements which fold the sheet-material over the feather of the insole and against the rib, to remain at rest at the time of introduction of the work, so this will be made easy, and thereafter to be started in operation without effort on the part of the operator, I provide means controlled by the insole for connecting driving means to actuating means for the operating elements. This may be effected by the movable work-supporting table, which carries the insole against an anvil, this anvil furnishing a portion of cutting mechanism acting upon the margin of the sheet-material. The anvil, in turn, through a carrier upon which it is mounted and which it moves, releases a latch for a connecting member joining the actuating means to the driving means. This action may similarly control movement of the carrier by which the work is advanced for the operations upon it. The carrier is preferably retained temporarily in the position to which it is moved by the action of the work upon the anvil and is released as an incident to the control of the machine by the operator at the termination of an operation upon the margin of the sheet. Upon such ending of an operation, the margin-folding and -cutting members are located in predetermined positions to make them ready to act upon the next work-piece. To facilitate manipulation of the work and to produce a smoother disposition of the divided marginal portion of the sheet-material formed by the cutting member, the length of feeding steps is made variable by means arranged for actuation by the operator during the operation of the machine. Thus, if when operating upon the more sharply curved peripheral portions these steps are shortened while the cutting rate remains the same, the operator will have more time to turn the work, and the marginal divisions will be narrower and will lie more smoothly when pressed against the insole-rib. With the work-supporting and the margin-cutting, -folding and -feeding members, a member cooperates to clamp the work upon the support. This clamping member, in the present invention, is carried by a lever which is connected for its actuation by a cam device to an oscillatory member for moving the cutting, folding and feeding members.

In an application for improvements in Machines for operating upon insoles and methods which may be performed thereby, filed in my name in the United States Patent Office on March 10, 1938, and bearing the Serial Number 195,116, there are claims generic to certain features of the present invention.

In the accompanying drawings,
 Fig. 1 is a top plan view of a particular embodiment of my invention, with parts broken away;

Fig. 2, a broken front elevation;
Fig. 3, a similar side view;

Figs. 4 and 5, side elevations upon a larger scale than Fig. 3, showing, respectively, the operating elements in their normal relation and in engagement with the work preparatory to feeding;

Fig. 6, an irregular, horizontal section generally on the line VI—VI of Fig. 3;

Fig. 7, a partial elevation, with the parts positioned as in Fig. 5 but viewed from the opposite side of the machine;

Fig. 8, a broken front elevation, illustrating the elements more closely associated with the work but omitting the anvil;

Fig. 9, a top plan view of the carrier for the work-engaging elements;

Fig. 10, a detail in perspective of the knife and folder, particularly showing the means for depressing the latter;

Fig. 11, an enlarged detail in broken side elevation, the work appearing as clamped, ready for the operation upon it;

Figs. 12 and 13, views similar to Fig. 11, taken, respectively, from the right and left of the machine at the completion of the cutting and folding operations;

Fig. 14, a detail in perspective of the cutting and folding means ready for operation, as seen from the left at the front of the machine;

Figs. 15 and 16, horizontal sectional details, taken in planes just above the work-engaging elements, with these, respectively, at the beginning and end of the feeding strokes;

Fig. 17 shows in perspective an insole with its cover-sheet applied and ready for folding;

Fig. 18 is a like view of the covered insole, and

Fig. 19, a view similar to Fig. 18 of the forward extremity of the covered insole, bringing out the advantage of a decrease in the extent of work-advance.

The work to be performed by this invention will be made clear by consideration of Figs. 17 and 18 of the drawings. In Fig. 17 appears an insole I of the Economy type, which has, in addition to the usual body a, a double-lipped rib b, a reinforcing sheet c of fabric and a sheet s of leather or a leather substitute cemented to the tread or foot-contacting surface of the body. This sheet s covers the forepart of the insole, extending from approximately the breast-line to beyond the toe-end, it being of sufficient size to furnish a margin projecting some distance outside the insole-periphery. The cement employed for attaching the sheet s may be latex or some similar substance which retains its adhesive properties when dry. The present apparatus completes the application of the cover-sheet s, it folding the extended margin of the sheet up against the edge of the insole, measuring the width of margin necessary to reach the top of the rib b, cutting it along the line determined by this measurement, at the same time slashing the margin to produce divided portions d, and pressing these firmly against the feather f of the insole and the outer face of the rib b. The thus-positioned margin of the sheet s is held in place by the adhesive, the divided portions d accommodating themselves to the peripheral curvature 70 of the insole. This is as shown in Fig. 18.

The illustrated machine includes a column 10 (Fig. 3) upon which are carried, one upon another, a lower casing-section 12, an upper casing-section 14 and a cover 16. Depending from the upper section into the lower are opposite brack-

ets 18, 18 (Fig. 1). Upon these brackets and upon the upper section itself, the major portion of the driving and actuating elements of the machine are supported. By removing the securing screws 19, which pass through the cover and upper section and are threaded into the lower, and making a limited number of disconnections, the upper casing-section with the supported elements may be removed as a unit. This gives easy access to all these parts for inspection or repair. The lower section of the casing is adapted to contain oil to lubricate the various connections by splash-effect. Arranged at the front of the casing for vertical oscillation in parallel planes are horizontally extending arms 20, 20, pivoted at 21, 21 upon the casing-section 12 and carrying at their outer extremities a reciprocating plunger or holder member 22. The pivotal points are spaced from each other vertically to give a parallel motion, thus maintaining the axis of the member 22 against angular displacement. Upon the upper extremity of the holder member, a work-supporting table 24 is rotatable upon ball-bearings 26. From the holder depends a rod 28, extending through an opening in a bracket 30 projecting from the casing. Surrounding the rod, and abutting at its upper end against the holder and at its lower against a screw 32 threaded vertically into the under side of the bracket, is a spring 34. The screw 32 has a longitudinal passage to receive the rod. The spring holds the table normally raised by a force dependent upon the adjustment of the screw and to an extent determined by a collar 36 fast upon the rod and contacting with the lower end of the screw. Fulcrumed at the front of the holder 22 is a bell-crank-lever 40, a substantially horizontal arm of which is held normally raised by a tension-spring 42, connecting it to the holder and exerting less force than the table-spring 34. The inner end of the lever-arm is joined by a rod 44 to an unillustrated treadle. An upstanding arm of the lever 40 is arranged for engagement with a rod 46 sliding horizontally in the holder. With the opposite end of the rod contacts the head 48 of a cylindrical slide 50, movable horizontally in a guide-block 52. In ways in the head 48 is held by a slot-and-screw connection 54 for vertical adjustment, the shank of an edge-pressing member 56 extending over the work-supporting surface of the table 24 and having a vertical portion 57, upon which is a work-contacting surface curved outwardly in the direction of work-advance (Figs. 15 and 16). The block 52, with the pressing member, is caused to move vertically, longitudinally of the axis of the table, by the engagement of said table with the edge-pressing member and with an extension 58 from the block which projects under the holder 22. It is guided in this movement by a pin 60 depending from the block and a pin 62 entering an opening in the block. The opening receiving the pin 60 of the guide-block is in a forwardly extending arm 64 of a carrier 66, and the pin 62 rises from said arm. This carrier is arranged to oscillate horizontally, in a direction substantially parallel to the work-supporting surface of the table 24, about a spindle 68 held in the casing-sections 12 and 14. The carrier may be raised against the expansive force of a spring 72 interposed between it and the section 14 and surrounding the spindle. The member 56 is urged normally outward (Fig. 4) by a torsion-spring 74 which surrounds a spindle 76 (Fig. 8) rotatable in the carrier-arm 64. One

extremity of the spring is secured to the spindle, while the other bears against the head 48. To vary the force which the spring exerts upon the member 56, it may be tensioned by turning a finger-piece 78 fast upon the spindle. Said spindle is then fixed in the proper position by one of a series of circumferential depressions 80 formed in the hub of the finger-piece and receiving a pin 82 projecting from the carrier-arm. Normally, the table 24 is elevated by its spring 34, and the member 56 held at its inmost point upon the table by the spring 74, both the table and member being then in their active positions. When the operator wishes to insert an insole in the machine for the operation upon it, he lowers the rod 44. This first swings the lever 40 about its fulcrum, forcing its vertical arm against the rod 46 and pressing back the slide 50 against the force of its spring. This continues until the oscillation of the lever is stopped by the engagement with the holder 22, at which time the member 56 has been carried to the periphery of the table. Further downward pull upon the rod 44 is transmitted to the holder, which is lowered against the bracket 30, the spring 34 being compressed. The member 56 descends with the table, the holder pressing against the slide-extension 58 to depress the guide-block 52 upon the carrier-arm 64. The operator introduces the insole into the machine from the right, sliding it over the table. Then, the rod 44 is released, permitting the table to be again elevated and the member 56 to be moved inwardly over the upper surface of the table by their springs. At this time, the inner vertical face of the portion 57 contacts with the under side of the marginal portion of the sheet s, turning it up and forcing it against the edge of the insole-body a. In addition to the edge-pressing member 56, the carrier 66 has mounted upon it the following elements, which act upon the work in co-operation with the table (Figs. 11 to 14): An anvil 88; a slashing and trimming knife 90 for the cover-sheet, acting against the anvil, the knife and anvil together furnishing cutting mechanism; a folding and pressing block or finger 92, movable with the knife and acting upon the cover-sheet; a folding and clamping block 94, holding the sheet to the anvil for the cut, and a finger 96, retaining both the insole-feather and the margin of the sheet in position for the folding and cutting operations.

A work-guiding and clamping member 97, between which and the anvil 88 the rib b of the insole I is presented over the table 24, is mounted upon a horizontally extending lever 98, fulcrumed at 100 upon the casing-section 14. As appears in Figs. 2 and 13, the guide 97 is inclined inwardly and forwardly, so it may readily enter and occupy the channel at the inner side of the rib b, and has a corner 102 to lie within the angle of said channel and a surface 104 against which the layer of fabric c may bear. It may be serrated upon its under side at 105, to more effectively retain the work upon the table and is secured to the lever 98 for universal adjustment by intermediate members 106 and 107 and three slot-and-screw connections 108 (Fig. 4).

The anvil 88 is horizontally adjustable in ways upon the lower extremity of a bracket 109, being clamped in position by a screw 110 (Figs. 2 and 7). The bracket is adjustable vertically in ways at the outer end of an upper arm 111 projecting from the carrier 66. Its movement upon the arm 75 is effected by a screw 112 threaded into the top

of the bracket, with its head turning in a depression in the carrier-arm. To take up lost motion in its support upon the arm and to hold the anvil-bracket in a definite position with relation to the knife, said bracket is urged down by an expansion-spring 113 interposed between a horizontal extension at the bottom of the bracket and the carrier-arm. The adjusted bracket, with the anvil, is fixed in position by a screw 114. The anvil has a recess 115 (Fig. 14) through which a portion of the knife 90 operates. The lower wall 116 of the recess and the corresponding vertical wall 117 below this recess furnish ledger-blades for co-operation with angularly disposed edges of the knife. The outer wall 118 of the anvil, below the recess, is inclined downwardly and inwardly to conform generally to the angle at which the insole-rib is disposed against the guide 97. The inner wall 120 is substantially vertical to support the margin of the sheet s, which is pressed against it by the member 94 during the slashing and trimming operation.

The knife 90 and the folding and pressing block 92 are carried upon a generally vertical bell-crank-lever 122 fulcrumed at 124 upon the carrier-arm 111. The knife is adjustable in horizontal ways in the divided end of the lever, it being clamped by a screw 126 (Fig. 14). It is L-shaped, having a horizontal trimming edge 128 and an adjacent vertical slashing edge 130 co-operating respectively with the anvil-walls 116 and 117, as previously indicated. The folding and pressing block 92 has a shank 123 sliding in ways in the forward face of a terminal-portion 121 of the lever 122, to which it is attached by the screw 126. The upward travel of the shank in the ways is limited by the head of a screw 129 threaded into the terminal-portion, and against this screw-head it is yieldably held by a spring 125 secured to said terminal-portion by a screw 131 (Fig. 13). The block 92 has an outer end wall 132 substantially parallel to the wall 104 of the channel-guide 97. Along the bottom of the wall 132 is a bead or projection 133. Initially, the block is so held by the spring 125 that its lower surface 134 clears the edge of the feather f of an insole resting upon the table 24, as the lever 122 carries the block outwardly, or inwardly with respect to the periphery of the insole. Then, an upwardly and rearwardly inclined surface 135 of the block engages a roll 136 rotatable about a horizontal axis upon a holder 137. The holder is guided for vertical adjustment on a plate 138 and fixed in place by a slot-and-screw connection 140. The plate is held against movement upon the lower portion of the arm 111 of the carrier 66 by a projection 141 (Figs. 7, 8 and 10), secured by screws 142, 142. The inclined surface 135, by its engagement with the roll, cams down the block. This causes the projection 133, passing inwardly well above the edge of the insole, to descend and rub over the margin of the sheet s above the feather, pressing it thereon and into the angle of the outer channel. Finally, the lower surface 134 of the block is forced down upon the entire width of the sheet-margin above the feather to complete its adhesion. In the oscillation of the lever 122, the outer surface of the terminal-portion 121 preferably slides upon the adjacent face of the plate 138. This guides the knife 90, steadyng it during its cutting stroke.

Fulcrumed at 143 upon the carrier 66 is a bell-crank-lever 144 (Fig. 5). To a downwardly extending arm of this lever, there is adjustably se-

cured by a slot-and-screw connection 145 the shank of the folding and clamping block 94. This block has a vertical, work-engaging face 146 (Fig. 12), which co-operates with the face 120 upon the anvil 88 below the recess 115 to hold the margin of the sheet *s* for cutting and thereafter during the feeding of the work, as will later be described. An outwardly extending, generally horizontal, upper arm of the lever 144 lies below a contact-roll 148 upon a projection 150 from the hub of the lever 122. The fulcrum-spindle 143 of the lever 144 is surrounded by and connected to a torsion-spring 152 (Fig. 2), which acts to force the arm of the lever 144 constantly against the roll 148. The face 146 of the clamping block is therefore held initially away from the anvil-face 126 by the roll and is permitted to approach said face 120 in advance of the knife 90, as the latter is actuated by the lever 122.

The retaining finger 96 is secured by a slot-and-screw connection 153 for adjustment longitudinally of an arm 154. This arm is arranged to turn on the carrier 66 about the spindle 124 and is held yieldably in to urge the finger 96 toward the edge-pressing member 56 by a spring 155, which joins the arm to the carrier. The movement of the arm under the influence of the spring is limited by a pin 156 projecting from one side of the hub of the arm, this pin lying in a slot in the head of the spindle 124. The lower portion of the finger is bent forwardly to lie close to the side of the anvil 88 (Fig. 2) and normally somewhat outside its wall 120, it being situated inwardly of the insole being operated upon from the knife 90. At its lower extremity, it is so related to the work-supporting surface of the table 24 that it will admit beneath it the feather of an insole, yet will retain this against substantial upward deflection. At its inner vertical edge 157, it restrains the margin of the cover-sheet *s* from falling upon the feather and adhering irregularly thereto before the associated operating elements lay it over said feather and against the rib *b* (Figs. 11 and 12). As such elements act, the spring 155 allows the finger to yield, so it travels toward the rib for each cutting and folding stroke and then returns to its initial position.

Considering now the means for imparting to the work-engaging elements their operating movements upon the carrier 66 and to this carrier its oscillation through which the work is fed for the successive operations upon it, these two purposes are respectively effected by actuating mechanisms A and B. Referring particularly to Figs. 1, 3 and 6, there is journaled transversely in the lower ends of the casing-brackets 18 a crank-shaft 158. To this shaft, power is applied through a readily separable connection from a short driving shaft 159 rotatable in a bracket 160 secured to the outside of the casing-section 12. The removal of the shaft 159 prepares for the separation from the machine of the casing-section 14, with the various elements which it carries. The shaft 158 rotates continuously during the operation of the machine two cranks 161, 162 within the casing. The crank 161 is joined by a connecting rod 162^a to the lower end of a lever 163 fulcrumed upon one of the casing-brackets 18. The upper arm of the lever, together with a link 164, furnishes a vertically extending toggle-lever which transmits power to a horizontally extending toggle-lever 165, 166. The rear extremity of this toggle 165 is fulcrumed upon a spindle fixed across the rear of the casing. The forward end of the toggle 165 is articulated to a substantially

vertical arm 166 arranged to turn about a horizontal spindle 167 fixed in the casing-brackets. The arm 166 oscillates uninterruptedly while the shaft 158 is in rotation. Secured to the upper extremity of the arm 166 is a contact-piece 168, which has a downward projection 170. To communicate intermittently the movement of the arm to the operating elements, there is an arm 172 arranged to oscillate about the spindle 167. To an upward and rearward extension 176 of the arm 172 is joined a link 177 for actuating the lever 122 carrying the knife 88 and the folding and pressing block 92. Pivoted upon a spindle 178 fixed in the arm 172 is a connecting arm 180, in the upper rear portion of which is a depression 182 for the reception of the projection 170. Beyond the depression, toward the end of the connecting arm, is a curved surface 183. This surface may be swung against the projection and ride upon it, until, as the arm 166 oscillates, the depression comes into registration with said projection. Then, when the depression is seated upon the projection as a result of upward movement of the arm 166 under the influence of a tension-spring 184 joining its outer extremity to the arm-extension 176, the arm 166 will be coupled to and will drive the arm 172 and the link 177. It will be observed that as the crank 161 turns through 360° in the direction of the arrow in Fig. 3, the straightening of the toggle 165 will give a rest-period, during which occurs the coupling action between the depression and the projection. Then, the toggle is broken upwardly to swing the arm 166 to the right to actuate the knife 88 and block 92, the channel-guide and presser-foot 97 at this time rising under the influence of a cam-slot 186 in the lever 98, this slot receiving a roll 188 surrounding the spindle 178. After this, the toggle is maintained broken to hold the engagement of the elements 88 and 92 with the work, while the feeding movement of the carrier 66 takes place. Then the toggle is again straightened to withdraw the knife and the block, while the cam-slot 186 causes the presser-foot 92 to descend to its work-clamping position. This allows the reverse movement of the carrier in preparation for the succeeding operating cycle and locates the presser-foot in its work-guiding relation.

The above-indicated coupling action by the arm 180 between the arms 166 and 172 is preferably under the control of the work when this is in operating position. Pivoted upon the casing-section 14 is a latch 199, which normally engages at its inner end a short upward extension 192 of the contact-arm 180. This latch holds the arm 180 down, so the depression 182 is spaced from the projection 170, and the driving arm 166 and driven arm 172 are disconnected. The latch 199 is geared at 194 to a short lever 196 fulcrumed at the top of the casing. Upon a forward extension of this lever a block 198 is pivoted, this lying within a horizontal slot in an arm 200 projecting from a rod 202 rising from the carrier 66. Considering the release of the latch so the operating elements may be actuated, the lower face of the anvil 88 of the cutting mechanism is normally spaced from the work-supporting surface of the table 24, so there is no lifting effect upon either the anvil or the carrier, to which the former is joined through the bracket 109 and the carrier-arm 111. The operator lowers the table by the treadle-connection 44, introduces an insole-blank beneath the wiper and releases the treadle. The spring 34 lifts the table, forcing the blank against

the bottom of the anvil, thereby elevating the arm 111 and the carrier 66 upon its spindle 68. Consequently, the carrier-arm 200 rises, swinging the lever 196 to lift the latch 190. This frees the connecting arm 180, and, drawn up by the spring 184, its depression 182 engages the projection 170, either directly or as a result of the travel of the surface 183 upon the projection. The action of the knife 90 and the folder and presser 92 at once begins, because of power applied by way of the link 177 from the driving connection thus established. The knife starts its cutting stroke, the block 92 traveling forward with it. As soon as the inclined surface 135 of the block is forced down by the roll 136, the pressure upon the work reacts upwardly to aid in the elevation of the carrier. In its raised operating relation, the carrier is temporarily maintained by a latch 206 (Fig. 4) pivoted upon the casing-section 12 and urged in by a tension-spring 208 joining it to the arm 30. The latch passes beneath a shoulder 210 upon the carrier. An eccentric-mounting 212, upon which the latch is pivoted, facilitates the adjustment of its engaging end with relation to the shoulder. When, upon completion of the operation upon the insole-blank, the table 24 is lowered for the removal of the work, a portion of one of the supporting arms 21 strikes a contact-screw 216 threaded through a tail 218 of the latch 206. The carrier 42 is thereby released, to be returned to its initial position by gravity and by the spring 72.

The carrier 66 is oscillated to feed the work forward for successive cutting and folding operations, while the operating instrumentalities are in engagement with said work. This movement of the carrier is produced by the actuating mechanism B, which is driven from the crank 162. The length of the feeding step is indicated by the angle between the dash-dot lines in Figs. 15 and 16. Since the crank 162 is 90° behind the crank 161, which has already been considered in connection with the description of the manner of actuating the cutting and folding means, and since this feed-crank acts through similar toggle mechanism, the opposite movements of the carrier to advance work and to return for the succeeding step of feed are performed alternately with the movements of such cutting and folding means. That is, the carrier rests when the cutting and folding elements assume their active positions, the presser-foot being withdrawn; produces feed while the cutting and folding elements are held in engagement with the work; again rests, as the presser-foot acts and the cutting and folding means are withdrawn; and finally returns idly to the initial position with the cutting and folding means. The mechanism B is in most respects the same as the mechanism A, and the parts more exactly corresponding to those of the mechanism A are designated by the same characters and will not be described. From Fig. 1, it will be seen that the latch 190 is common to the two mechanisms, so the elevation of the carrier under the control of the work renders both effective. When the latch is released, and driving engagement is established for the mechanism B, a link 220 actuated by the horizontal toggle 165 of said mechanism transmits movement to an arm 222 pivoted at 224 upon the casing-section 14 (Fig. 6). Oscillating with and below the arm 222 is an arm 226, which at its under side has a guide-channel to receive a block 228. Turning in a vertical bore in this block is a pin 230, rising from a slide 232 supported for reciprocation along an arm 234

projecting from the carrier 66 parallel to the arm 226. As the arm 222 is oscillated by the actuating mechanism B, so too will be the arms 226 and 234, the latter imparting the feeding movement to the carrier and the operating elements. It will be obvious that the arc through which said operating elements are swung by the carrier, and therefore the length of the feeding steps, will vary according to the position of the slide 232 upon the arm 234 and the corresponding location of the block 228 in the arm 226. To enable the operator to govern the feed, I provide means by which these connecting elements between the two arms may be shifted readily, while the machine is in operation. Fulcrumed about a spindle 240 (Fig. 4) fixed near the bottom of the carrier is a vertically disposed bell-crank-lever 242, an upwardly extending arm of which is united by a link 244 to the slide 232. To an outwardly extending arm of the bell-crank is joined a link 246 arranged for convenient actuation by the operator, as through a treadle. A torsion-spring 248 (Fig. 2), secured at its ends to the spindle 240 and the lever 242, so holds the connecting elements that the slide and block are normally in proximity to the outer ends of their arms, giving feeding steps of the maximum length. If there is some condition making desirable a less rapid advance of the work, as at a portion of sharp curvature of an insole, the operator depresses the link 246, carrying the connection between the arms 226 and 234 toward the axis of oscillation of the carrier. The length of the feeding steps is therefore shortened proportionately to the shift of the connection. The extremes of movement of the lever 242 and of the elements which it controls may be adjustably determined by a lateral pin 243 movable with the lever between opposite stop-screws 245, 245. These screws are threaded through a two-armed bracket 247 fixed upon the carrier. This control of the feed is of especial utility in connection with the smooth laying of the slashed margin of the cover-sheet s against the insole-rib 6. As the contour of the rib is more sharply curved, as at the toe, the wider divided portions overlap considerably and tend to full instead of lying flat. By diminishing the length of the feeding steps, while the cutting rate remains the same, the number of slashes made in a unit of length of the rib is increased. With the resulting narrow divisions, the overlap may be reduced to a minimum, and the ideal condition illustrated in Fig. 19 closely approached. The operator also has more time to manipulate the work.

After the machine has been in operation and is stopped by the lowering of the table 24, with the consequent release of the latch 206 and the connecting arms 180 of both actuating mechanisms A and B from the latch 190, the arms 172 should be brought to rest in predetermined angular positions. This is to cause the elements which operate upon the work to be in the correct relation for the initiation of the machine-cycle, when actuating engagement of the connecting arms 180 and the driving arms 166 is re-established. Further, the driven arms 172 should be at their extreme forward positions as the toggles 165 are straightened and are substantially at rest. This relation allows the proper engagement of the depressions 182 with the projections 170. Considering now only the arm 172 of mechanism A, this arm has projecting downwardly and forwardly from it a short extension 250 (Fig. 3), which is provided at its end with a surface of considerable area. Guided in a bracket 254 se-

cured to the casing-bracket 18 is a plunger 256 provided upon its head with an end-surface arranged for engagement with the end-surface of the lever. The plunger is urged upwardly by an expansion-spring 260 encircling its stem and abutting against a screw 262 threaded into the bracket at the lower end of the plunger-passage. Turning in the bracket is a horizontal spindle 263, and about this spindle is an eccentric-sleeve 264. Clamped upon the sleeve by a screw 265 is a latch 266 having a hooked end urged toward the edge of the head of the plunger 258 by a spring 268 interposed between the bracket and a depending tail of the latch. The relation between the plunger-head and the angular end of the latch may be adjusted by altering the position of the eccentric-sleeve within the latch. It will be observed that when the arm 172 is at rest, its position is always maintained by contact between the surfaces upon the plunger and the arm-extension 250, caused by the spring 260. As soon as oscillation of the arm 172 begins, one edge of the extension cams down the plunger to allow the hooked end of the latch to pass over the plunger-head. This head is now held away from the extension, save for a slight contact at that extreme position of the arm which caused the latching. The latched relation continues during the operation of the machine. Upon depression of the table 24 and the consequent lowering of the latch 190 to engage the arm 180 and disconnect the arm 172 from the driving means, the spindle 263 is rotated anticlockwise (Fig. 3). This is accomplished by a link 274 which joins the latch 190 to an arm 276 fast upon the spindle. Also secured to the spindle between the latch 266 of mechanism A and the corresponding latch of mechanism B is a bell-crank-lever 278. Upon rotation of the spindle, an upwardly extending arm of this lever presses against a pin 280 projecting from one side of the latch 266. Then, as the force exerted by the plunger 256 against said latch is relieved by the previously mentioned depression of the plunger at one extreme of movement of the lever-extension 250, the latch releases the plunger and resumes its place against the side of the head, ready for the initiation of the next operation. Since the timing of the actuating mechanisms A and B is different, the releasing movement which the link 274 imparts to the latch 266 of mechanism A is yieldably transmitted to the latch of mechanism B. A horizontal arm of the bell-crank-lever 278 is connected by a spring 282 to a horizontally extending arm of a bell-crank-lever 284 arranged to turn upon the spindle 263. The spring holds the forward end of the lever 278 in normal contact with the opposite portion of the lever 284. An upwardly extending arm of this lever 284 engages the pin 280 upon the latch 266 for the plunger 256 of mechanism B, these elements corresponding to the like parts of mechanism A. During the earlier portion of this unlatching movement of the lever 278, the latch of mechanism B will resist actuation on account of the pressure of its plunger, and the spring 282 will yield. But when the extension of the lever 172 of mechanism B attains an angle at which the opposite plunger is lowered to the maximum extent, the force applied through the spring is sufficient to unlatch said opposite plunger which establishes the normal position of its lever 172, as has been explained in connection with the mechanism A.

The apparatus of my invention operates in the

following manner. The driving arms 166 of both the mechanisms A and B are in constant oscillation under the influence of the shaft 152, the arms 172 and the work-engaging elements which they actuate being at rest in the positions shown in Figs. 3 and 4 of the drawings. The operator lowers the table 24 through the treadle-connection 44, this simultaneously moving back the edge-passing member 56. An insole I with its adhering sheet s is then placed upon the table, with the right-hand end of the rib b, as viewed from the toe-extremity, between the face 104 of the channel-guide 97 and the face 118 of the anvil 88. The rear edge of the margin of the sheet is turned up between the anvil and the retaining finger 96 at the inner side and the edge-pressing member 56, the knife 90 and the blocks 92 and 94 at the outer side. The treadle is then released, and the table allowed to rise, the member 56 moving inwardly over said table. The wall 57 raises the margin of the sheet s and presses it against the edge of the insole-body, at the same time holding the inner face of the rib b against the guide 97. The elements are now as illustrated in Fig. 11. Since all the elements which operate upon the work are at rest, its introduction into the machine may be effected quickly and accurately. When the feather f of the insole is forced by the ascending table against the bottom of the anvil, it lifts the carrier 66, which is retained in operating position by the latch 206. The carrier swings up the latch 190 to release the arm 180 of the actuating mechanism A. Under the influence of the spring 184, the depression 182 of the arm is caused to seat itself upon the projection 170 of the constantly oscillating driving arm 166, which is thus joined to the arm 172 to be driven. This movement of the arm 172 is effected, with alternate periods of activity and rest, through the double-toggle devices 163, 164 and 165, 165 of mechanism A. The link 177 swings the lower extremity of the lever 122 forward, this carrying with it the knife 90 and the block 92. As the roll 148 of the lever rises, it frees the folding block 94, so this travels in advance of the knife against the margin of the sheet s, carrying this across the insole-feather f and clamping it against the anvil-face 120. The finger 96, held out close to the edge of the insole against the margin of the sheet by the spring 155, has during this time performed two functions. Its end has prevented the feather of the insole from curling up to interfere with the movement of the blocks 92 and 94, and it has held the sheet-margin from falling upon the feather and adhering to it before it has been cut and properly folded by the blocks. The finger yields inwardly, so the action of the cutting and folding means is not interfered with. With the margin pressed against the anvil by the block 94, the edge 130 of the knife, co-operating with the vertical edge of the anvil, slashes the margin of the sheet in a direction substantially at right-angles to the feather of the insole to allow turning up the peripheral excess of material without fulling. The edge 128 of the knife, operating across the horizontal anvil-edge, trims off any excess of the margin which would project above the insole-rib b. After these cuts are made, the divided portion d is acted upon by the block 92. Its face 132 engages the portion d at such a distance above the feather f that there is no danger of contact with the edge of said feather. Then, as the inclined surface 135 passes beneath the roll 136, the block descends, wiping the divided margin across 75

the feather. Finally, by the surface 134, it presses the margin firmly down and into the angle of the outer channel by the projection 133, while the end-surface 132 of the block forces the end of the portion *d* against the outer face of the rib *b*. The elements in this relation may be seen in Figs. 12 and 13. The latex with which the parts are coated causes the adhesion of the sheet-margin to the insole-edge and the feather- and rib-surfaces under the influence of the pressure applied by the member 56 and the block 92. This pressure upon the rib is resisted by the surface 104 of the channel-guide 97.

In connection with the folding block 94, there should be noted its effect in measuring the length of the sheet-portions *d* as they extend from the edge of the insole-body *a*. Since the feather varies in width at different points about the periphery of the insole, and as the cut at the end of each portion *d* is made by the edge 128 of the knife 90 before the margin of the sheet *s* is laid against the outer face of the rib *b*, the different lengths of the portions *d* must be determined before the cuts are made. The insole is always located in a definite radial position upon the table 24, with respect to the termination of the cutting stroke of the knife 90, by the channel-guide 97 inside the rib and the edge-pressing member 56 and the anvil 88 outside said rib. Outside the wall 120 of the anvil, the edge of the insole will extend for different distances, depending upon which peripheral portion the operation is being performed. This will be evident from an inspection of Figs. 17 and 18, which show the differences in the width of the feather *f*, and Figs. 12 and 14, illustrating the relation of the machine elements to the work. As the member 94 folds in the margin of the sheet over the feather, the yielding action furnished by the spring 152 allows the member to lay upon the feather, up to the bottom of the anvil-wall 120, whatever width of sheet-margin may be necessary. This leaves to be added to the length of the sheet-portion *d* an amount equal to the thickness of the bottom of the anvil, plus the height of the rib. The first of these is constant, and the second, substantially so. A proper vertical location of the knife-edge 128 and its co-operating anvil-edge will, therefore, provide for the correct length of each portion *d*. As a result of this, when the cut portion is laid in place upon the rib, its end will lie approximately at the top of the rib, regardless of the width of the adjacent portion of the feather.

A covering step has been completed (Fig. 15), during which the channel-guide and presser-foot 97, which have been holding the work upon the table by the engagement of its end 105, is raised to free it for advance in preparation for the next operation. This movement of the element 97 results from the action of the roll 188 of lever 172 upon the cam-slot 186 of the presser-foot-lever 98. A period of rest of the mechanism A now occurs, while the mechanism B is made active by connection between its arms 166 and 172 through the arm 180, the last-mentioned arm being released by the latch 190 at the same time as the corresponding arm of mechanism A. But the driving and driven arms of mechanism B are coupled later in the cycle, because of the ninety-degree separation of the driving cranks 161 and 162 of the respective mechanisms. Through the link 220, the carrier 66 is swung about its spindle to advance a step work grasped by the forming elements, which have cut, measured, folded and

pressed the sheet *s* (Fig. 16). The edge-pressing member 56 travels with these carrier-borne elements because of its mounting upon the carrier-arm 64. The table 24 at this time turns freely upon its ball-bearings 26 to lessen the resistance to work-advance. The operator may vary the rate of feed, while the operation is progressing, so as to reduce it, as when rounding the sharply curved toe-portion of a blank. This is accomplished by shifting the connection between the arms 226 and 234 through depression of the treadle-connection 246. The operator is given more time to make the turn, and the width of the marginal divisions is simultaneously narrowed, so they may lie more smoothly upon the rib *b*. Following the action of mechanism B to produce this feed, mechanism A again becomes effective to carry the forming elements away from the work and to lower the channel-guide and presser-foot to hold said work against the table, so reverse movement is prevented. As the last step of the cycle, the carrier returns the forming elements to their initial positions. There are produced in this manner alternate forming and feeding actions, until the opposite end of the breast-line is reached, and the application of the margin of the cover-sheet *s* to the insole *I* is completed. At the close of the operation, the table 24 is drawn down by the treadle-connection 44 to facilitate the removal of the completed work. When this happens, engagement of one of the table-supporting arms 21 frees the elevated carrier 66 from the latch 206, and said carrier returns to its initial position. In so doing, it releases, by way of the latch 190 and link 274, the latches 266 of the plungers 256 of mechanisms A and B, which plungers have been held inactive by their respective latches while the arms 172 were in motion. Contact between the faces of the freed plungers and the extensions 250 of such arms holds the latter in a definite angular relation, ready for coupling at the initiation of the next operation, upon the lowering of the rod 44 by the operator, and with the work-engaging elements controlled by the arms in 45 their normal positions.

Having described my invention, what I claim as new and desire to secure by Letters Patent of the United States is:

1. In a machine for folding over the edge of a ribbed insole sheet-material secured to the surface opposite the rib, a support for the insole, a member movable across the feather of the supported insole to operate upon the margin of the sheet, and a retaining member arranged to receive engagement of the outer margin of the insole before the folding of the sheet thereover.

2. In a machine for folding over the edge of a ribbed insole sheet-material secured to the surface opposite the rib, a support for the insole, a member movable across the feather of the supported insole to operate upon the margin of the sheet, and a retaining member movable across the insole-feather for engagement with the surface of the sheet opposite that thus operated upon.

3. In a machine for folding over the edge of a ribbed insole sheet-material secured to the surface opposite the rib, a support for the insole, a member movable across the feather of the supported insole to operate upon the margin of the sheet, and a retaining member yieldable transversely of the insole-feather.

4. In a machine for folding over the edge of a ribbed insole sheet-material secured to the sur- 75

5 face opposite the rib, a support for the tread-surface of the insole, a member movable across the feather of the supported insole to operate upon the margin of the sheet, and a retaining member yieldable transversely of the insole-feather and arranged for engagement with the margin of the sheet.

10 5. In a machine for folding over the edge of a ribbed insole sheet-material secured to the surface opposite the rib, a support for the insole, a cutting member acting upon the margin of the sheet, a retaining member for the sheet-margin, and means for moving the retaining member toward the cutting member.

15 6. In a machine for folding over the edge of a ribbed insole sheet-material secured to the surface opposite the rib, a support for the tread-surface of the insole, a cutting member acting upon the margin of the sheet, and a retaining member movable against the sheet-margin inwardly of the insole from the cutting member.

20 7. In a machine for folding over the edge of a ribbed insole sheet-material secured to the surface opposite the rib, a support for the tread-surface of the insole, a folding and pressing member acting to force the margin of the sheet across the insole-feather, and a retaining member arranged for engagement with the outer portion of the insole-feather before it receives the action of the folding and pressing member, the retaining member being yieldable as the folding and pressing member acts.

25 8. In a folding machine, a work-supporting table, means movable inwardly across the table to fold the work, and a finger having a substantially vertical surface for retaining a portion of the work against folding and movable inwardly across the table by engagement of said work.

30 9. In a machine for folding one work-piece about another work-piece, a work-supporting table, means movable inwardly across the table to fold the first of the work-pieces, a retaining finger movable across the table and having separate surfaces for engagement with the respective work-pieces, and a spring urging the finger outwardly across the table against the action of the first of the work-pieces.

35 10. In a folding machine, a work-supporting table, a carrier mounted to oscillate above the table, cutting and folding members movable upon the carrier, means for oscillating the carrier to advance the work in the engagement of the cutting and folding members, and a finger pivoted upon the carrier and movable by the work.

40 11. In a folding machine, a work-supporting table, a carrier mounted to oscillate above the table, cutting and folding members movable upon the carrier, means for oscillating the carrier to advance the work in the engagement of the cutting and folding members, a finger pivoted upon the carrier for contact with the work, and a spring connecting the finger to the carrier.

45 12. In a machine for folding over the edge of a ribbed insole sheet-material secured to the surface opposite the rib, a support for the insole, a supporting member movable transversely of the feather of the supported insole, a cutter mounted upon the supporting member to act upon the margin of the sheet-material, and a member movable by the supporting member and bodily upon said supporting member to force the material against the insole-rib and insole-feather.

50 13. In a machine for folding over the edge of a ribbed insole sheet-material secured to the surface opposite the rib, a support for the insole, a

55 supporting member movable transversely of the feather of the supported insole, a cutter mounted upon the supporting member to act upon the margin of the sheet-material, a folding and pressing member mounted to move upon the supporting member, said folding and pressing member acting to force the material against the insole-rib in the cutting movement of the cutter, and means for moving the folding and pressing member upon the supporting member to force the material 10 against the insole-feather.

60 14. In a machine for folding over the edge of a ribbed insole sheet-material secured to the surface opposite the rib, a support for the tread-surface of the insole, a supporting member movable transversely of the feather of the supported insole, a cutter mounted upon the supporting member to act upon the margin of the sheet-material, a folding and pressing member mounted to move upon the supporting member, said folding and pressing member acting to force the material against the insole-rib in the cutting movement of the cutter, and a relatively stationary member into contact with which the folding and pressing member is moved by the supporting member to force the material against the insole-feather.

65 15. In a machine for folding over the edge of a ribbed insole sheet-material secured to the surface opposite the rib, a support for the tread-surface of the insole, a supporting member movable transversely of the feather of the supported insole, a cutter mounted upon the supporting member to act upon the margin of the sheet-material, a folding and pressing member mounted to move upon the supporting member, said folding and pressing member acting to force the material against the insole-rib in the cutting movement of the cutter, a relatively stationary member into contact with which the folding and pressing member is carried by the supporting member thereby moving the folding and pressing member upon said supporting member to force the material against the insole-feather, and a spring resisting the last-mentioned movement.

70 16. In a folding machine, a work-supporting table, a lever arranged to oscillate across the table with its end moving substantially parallel thereto and provided with ways extending in a substantially vertical direction, and a folding and pressing block movable in the ways upon the lever and co-operating with the table.

75 17. In a folding machine, a work-supporting table, a lever arranged to oscillate across the table, a folding and pressing block movable upon the lever and co-operating with the table, a spring urging the block upon the lever away from the table, and means for forcing the block toward the table.

80 18. In a folding machine, a work-supporting table, a lever arranged to oscillate across the table, a folding and pressing block movable upon the lever and co-operating with the table, said block being provided with an inclined surface, and a member with which the inclined surface contacts to force the block toward the table.

85 19. In a folding machine, a work-supporting table, a lever arranged to oscillate across the table, a folding and pressing block movable upon the lever and co-operating with the table, said block being provided with an inclined surface, a spring interposed between the lever and block, and a member with which the inclined surface contacts to force the block toward the table.

90 20. In a folding machine, a work-supporting

- table, a lever arranged to oscillate across the table and provided with ways, a knife carried by the lever, and a folding and pressing block movable in the ways upon the lever and co-operating with the table. 5
21. In a folding machine, a work-supporting table, a carrier arranged to oscillate above the table, a lever fulcrumed upon the carrier and oscillating across the table, a folding and pressing block movable upon the lever toward and from the table, and a member mounted upon the carrier and with which the block contacts to produce its movement upon the lever. 10
22. In a folding machine, a work-supporting table, a carrier arranged to oscillate above the table, a lever fulcrumed upon the carrier and oscillating across the table, a knife fixed in the carrier, a folding and pressing block movable upon the lever toward and from the table, and a member mounted upon the carrier and with which the block contacts to produce its movement upon the lever. 15
23. In a folding machine, the combination with folding means, of a rotatable work-supporting table, a guide-block movable longitudinally of the axis of the table, a cylindrical slide guided in the block and provided with a head, and an edge-pressing member carried by the head and extending over the table. 20
24. In a folding machine, the combination with folding means, of a rotatable work-supporting table, a guide-block movable longitudinally of the axis of the table, a slide guided in the block and provided with a head, an edge-pressing member carried by the head and extending over the table, a torsion-spring engaging at its ends the block and the head of the slide, and means arranged to vary the force of the spring. 25
25. In a folding machine, the combination with a work-supporting table, of an oscillatory carrier, a folding member movable on the carrier over the table, a block, pins by which the block is guided for movement upon the carrier longitudinally of the axis of the table, a cylindrical slide guided in the block, and an edge-pressing member carried by the slide and extending over the table. 30
26. In a folding machine, the combination with a work-supporting table, of an oscillatory carrier, a folding member movable on the carrier over the table, a guide-block movable upon the carrier longitudinally of the axis of the table, a slide guided upon the block, a spindle rotatable in the carrier, a spring surrounding the spindle and secured thereto and to the slide, and means arranged to turn the spindle and secure it in different positions. 35
27. In a machine for folding over the edge of a ribbed insole sheet-material secured to the surface opposite the rib, a member movable into engagement with the margin of the sheet to fold it over the insole-feather and against the rib, actuating means for the member, constantly operating driving means, and means controlled by the insole for connecting the driving means to the actuating means. 40
28. In a machine for folding over the edge of a ribbed insole sheet-material secured to the surface opposite the rib, members movable into engagement with the margin of the sheet to fold it over the insole-feather and against the rib, means for moving the folding members in engagement with the insole to advance it, actuating means for the folding members and advancing means, and means constantly operating driving means, and means 45
- controlled by the insole for connecting the driving means to the actuating means for both the folding members and the advancing means. 50
29. In a machine for folding over the edge of a ribbed insole sheet-material secured to the surface opposite the rib, a work-supporting table, cutting mechanism co-operating with the table, an actuating member for the cutting mechanism, a driving member for the actuating member, a member movable to connect the driving member and actuating member, and means controlled by the cutting mechanism to govern the movement of the connecting member. 55
30. In a machine for folding over the edge of a ribbed insole sheet-material secured to the surface opposite the rib, a movable work-supporting table, a reciprocating knife and a co-operating anvil associated with the table, the anvil being movable under the influence of said table, an actuating member for the knife, a driving member for the actuating member, a member movable to connect the driving member and actuating member, and a latch for the connecting member released by the movement of the anvil. 60
31. In a machine for folding over the edge of a ribbed insole sheet-material secured to the surface opposite the rib, a vertically movable table for supporting the insole, a carrier mounted for oscillation adjacent to the table and to move vertically, a reciprocating knife and a co-operating anvil mounted upon the carrier, the anvil being movable by the insole under the influence of the table, an actuating member for the knife, an actuating member for the carrier, driving means for the actuating members, members for connecting the actuating members to the driving means, a latch for the connecting members, and means for communicating the movement of the anvil to the latch to release the connecting members therefrom. 65
32. In a machine for folding over the edge of a ribbed insole sheet-material secured to the surface opposite the rib, a support for the insole, cutting mechanism co-operating with the support, a carrier for the cutting mechanism movable by force applied to said cutting mechanism, and means for temporarily retaining the carrier in the position to which it is moved. 70
33. In a machine for folding over the edge of a ribbed insole sheet-material secured to the surface opposite the rib, a support for the insole, cutting mechanism co-operating with the support, a carrier for the cutting mechanism movable by force applied to said cutting mechanism, means for temporarily retaining the carrier in the position to which it is moved, and means acting as an incident to the control of the machine by the operator for freeing the carrier from the retaining means. 75
34. In a machine for folding over the edge of a ribbed insole sheet-material secured to the surface opposite the rib, a movable support for the insole, cutting mechanism co-operating with the support, a carrier for the cutting mechanism movable by force applied to said cutting mechanism, means for temporarily retaining the carrier in the position to which it is moved, and means acting in the movement of the support for freeing the carrier from the retaining means. 80
35. In a machine for folding over the edge of a ribbed insole sheet-material secured to the surface opposite the rib, a vertically movable insole-supporting table, a carrier mounted for oscillation adjacent to the table and to move vertically, a reciprocating knife and co-operating anvil 85

mounted upon the carrier, the anvil being movable by the insole under the influence of the table, means arranged to move the table to press the supported insole against the anvil to move 5 said anvil and the carrier, and retaining means for the carrier as it is thus moved, said retaining means being released upon reverse movement of the table.

36. In a machine for folding over the edge of 10 a ribbed insole sheet-material secured to the surface opposite the rib, members acting upon the margin of the sheet to cut and fold it over the insole-feather and against the rib, means for moving the cutting and folding members, means 15 for connecting the members to and disconnecting them from the moving means, and means for locating the disconnected members in predetermined positions.

37. In a machine for folding over the edge of 20 a ribbed insole sheet-material secured to the surface opposite the rib, members acting upon the margin of the sheet to cut and fold it over the insole-feather and against the rib, a carrier upon which the members are movable, means for moving 25 the carrier to advance the work, means for moving the members upon the carrier, a cutting member acting to move the carrier, means controlled by the last-mentioned movement of the carrier for connecting the carrier and the cutting 30 and folding members to and disconnecting them from the moving means, and means for locating the disconnected carrier and members in predetermined positions.

38. In a machine for folding over the edge of 35 a ribbed insole sheet-material secured to the surface opposite the rib, members acting upon the margin of the sheet to cut and fold it over the insole-feather and against the rib and to feed the work, actuating mechanism for imparting to the 40 members their cutting and folding movements, actuating mechanism by which the members are moved to feed the work for cutting and folding, driving mechanism for each actuating mechanism, means for connecting the actuating mechanisms to and disconnecting them from their 45 driving mechanisms, and means for locating the disconnected mechanisms in predetermined positions.

39. In a machine for folding over the edge of a 50 ribbed insole sheet-material secured to the surface opposite the rib, members acting upon the margin of the sheet to cut and fold it over the insole-feather and against the rib and to feed the work, actuating mechanism for imparting to the 55 members their cutting and folding movements, actuating mechanism by which the members are moved to feed the work for cutting and folding, driving mechanism for each actuating mechanism, means for connecting the actuating mechanisms to and disconnecting them from their 60 driving mechanisms, means for locating the disconnected mechanisms in predetermined positions, and means for holding the locating means ineffective during the operation of the machine.

40. In a machine for folding over the edge of 65 a ribbed insole sheet-material secured to the surface opposite the rib, members acting upon the margin of the sheet to cut and fold it over the insole-feather and against the rib, an actuating member for the cutting and folding members, said actuating member being provided with

a contact-surface, a constantly operating driving member for the actuating member, means for connecting the actuating member to and disconnecting it from the driving member, a plunger engaging the contact-surface of the disconnected 5 actuating member to locate it, and a latch for holding the plunger in an ineffective position during the operation of the machine.

41. In a machine for folding over the edge of a 10 ribbed insole sheet-material secured to the surface opposite the rib, members acting upon the margin of the sheet to cut it and fold it over the insole-feather and against the rib, means for moving the members to feed the work in successive steps for cutting and folding, and means arranged for actuation by the operator during the 15 operation of the machine for changing the length of the feeding steps.

42. In a machine for folding over the edge of a ribbed insole sheet-material secured to the surface opposite the rib, members acting upon the margin of the sheet to cut it and fold it over the insole-feather and against the rib, a carrier upon which the members are movable, an actuating member for moving the carrier with the cutting and folding members to advance the work, connections to the actuating member to move the carrier, and means arranged for movement by the operator during the operation of the machine to vary the relation of the connections to the elements joined and thereby change the rate of advance of the work. 20 25 30

43. In a machine for folding over the edge of a ribbed insole sheet-material secured to the surface opposite the rib, members acting upon the margin of the sheet to cut it and fold it over the insole-feather and against the rib, a carrier upon which the members are movable, said carrier being provided with an arm, a movable arm adjacent to the carrier-arm, a device for connecting the arms and being variable in position longitudinally thereof, and an operator-actuated member for shifting the connecting device upon the arms during the operation of the machine. 35 40

44. In a machine for folding over the edge of a ribbed insole sheet-material secured to the surface opposite the rib, a support for the insole, members co-operating with the support and movable into engagement with the margin of the sheet to cut it and fold it over the insole-feather and against the rib and to feed the work, oscillatory members for moving the cutting, folding and feeding members, a lever, a member carried by the lever for clamping the insole upon the support, and a cam device for connecting one of the 50 55 oscillatory members to the lever to actuate it.

45. In a machine for folding over the edge of a ribbed insole sheet-material secured to the surface opposite the rib, a support for the insole, members co-operating with the support and movable into engagement with the margin of the sheet to cut it and fold it over the insole-feather and against the rib and to feed the work, oscillatory members for moving the cutting, folding and feeding members, from one of which oscillatory members is a projection, a lever provided with a cam-slot receiving the projection, and a member carried by the lever for clamping the insole upon the support. 60 65 70
